ATTORNEYS.

UNITED STATES PATENT OFFICE.

JAMES H. BAKER, OF WESTVILLE, OHIO.

FORGE-HAMMER.

SPECIFICATION forming part of Letters Patent No. 297,659, dated April 29, 1884.

Application filed October 24, 1883. (No model.)

To all whom it may concern:

Be it known that I, JAMES H. BAKER, of Westville, in the county of Champaign and State of Ohio, have invented certain new and useful Improvements in Die-Blocks for Forge-Hammers, of which the following is a full, clear, and exact description.

My invention relates to improvements in die-blocks for forge-hammers; and it consists 10 in the peculiar construction and arrangement of the parts, as hereinafter more fully set forth, and pointed out in the claims.

Reference is to be had to the accompanying drawings, forming part of this specification, 15 in which similar letters of reference indicate corresponding parts in both the figures.

Figure 1 is a perspective view of a die and die-block anvil, anvil-support, and part of the forge-hammer provided with my improvement. Fig. 2 is a side view of the same, the hammer being omitted.

The die A, which is shaped and formed according to the size, shape, and form that the clip, &c., are to have, is placed on a die-block 20 B, and is held on the same by suitable devices. The die-block is provided with track-bars C, projecting from the bottom and sides of the die-block, the lower edges of which track-bars rest on rollers D, journaled in vertically-adjustable brackets E, held on the sides of the anvil I. If desired, the rollers D can be held 30 in grooves in the top of the anvil, and flanges may be provided on the sides of the die-block in place of the bars C.

35 On the front of the die-block B a rack, F, is secured parallel with the said front, and in such a manner that the rack projects the distance of its width from the front of the said die-block. The rack can be fastened on the 40 die-block in any suitable manner, or can be made integral with the same. A short shaft, G, of any desired length, is journaled in the upper end of an upwardly-projecting arm or plate, H, secured to the front of the anvil I, 45 and on the inner end of the said shaft G a pinion, J, is rigidly mounted, which engages with

the rack F, and on the outer end of the shaft G a hand-wheel, K, or a crank-handle, or analogous device, is rigidly mounted, by means of which the shaft G and the pinion J can be 50 turned or revolved. By revolving the pinion the die-block B will be moved laterally—that is, in the direction of the length of the rack—and at right angles to the longitudinal axis of the striking-surface of the hammer L, held 55 above the die, which hammer can be arranged to swing or reciprocate vertically. The die-block can thus be shifted slightly after each stroke of the hammer, and thus the stock held in the die will be struck in a different 60 place, if desired, at each stroke, and will be widened, flattened, or plated out, as is necessary in making wagon-clips, plates having stems, and like work.

If desired, the anti-friction rollers D and 65 track-bars C can be dispensed with.

The rack and pinion can be combined by suitable mechanism with the hammer, to shift the die-block automatically after each stroke of the hammer.

Having thus described my invention, I claim as new and desire to secure by Letters Patent—

1. The combination, with the movable die-block B, of the rack F, secured on the same, the shaft G, the pinion J, mounted on the 75 same, and engaging with the rack F, and of the hand-wheel K on the outer end of the shaft, substantially as herein shown and described.

2. The combination, with the anvil I and 80 the movable die-block B, of the rack F, secured on the die-block, the arm H on the anvil, the shaft G, held to turn in the arm H, the pinion J, mounted on the shaft G and engaging with the rack, and of the hand-wheel 85 K, mounted on the outer end of the shaft G, substantially as herein shown and described,

JAMES H. BAKER.
